UNITED STATES PATENT OFFICE

ROLLS PERCIVAL LINK, OF LONDON, ENGLAND.

AUTOGRAPH-RECORDER.

SPECIFICATION forming part of Letters Patent No. 674,209, dated May 14, 1901.

Application filed January 2, 1901. Serial No. 41,895. (No model.)

To all whom it may concern:

Be it known that I, ROLLS PERCIVAL LINK, salesman, a citizen of the United States of America, residing at London, England, have 5 invented certain new and useful Improvements in Time and Autograph Recorders and the Like, of which the following is a specification.

This invention relates to recorders of the 10 kind or class wherein an autograph-record is made on a strip of paper or other material, together with a record made by printing-wheels or other automatic mechanism, and the said invention is intended chiefly for recording the times of entry and exit of work 15 people and others to and from the works or place of business and for receiving at the same time autograph-records of such persons whereby they may be identified.

20 The strip of paper or the like upon which the records are made has two movements imparted to it during each complete record—viz., a backward movement and a forward movement. The forward movement is, however, 25 greater than the backward movement, so that the said strip on the whole receives a progressive forward movement, and the successive records are thereby obtained in due order on the strip. By this means it is possible to arrange 30 that the actual position where the autograph is made shall be so remote from the time-wheels or other automatic printing mechanism that ample and convenient room is allowed for writing on the recording-strip, while at the 35 same time the two records—viz., that made by the automatic wheels and the autograph—are brought close together. The strip is first moved backward before the autograph-record is made and is then moved forward before 40 the automatic record is made. This to-and-fro movement of the strip constitutes an important feature of my invention.

Another important feature of my invention 45 is the arrangement of the spools or reels carrying the recording-strip on one side of the machine and the actuating mechanism on the other side so that the two are distinct and the recording-strip can thus be manipulated and inserted and removed when required 50 without difficulty.

Referring to the accompanying drawings, which illustrate how my invention may be

conveniently carried into practice, Figure 1 is a front elevation of the machine, partly in section, the front of the case being partially removed. Fig. 2 is a side view looking from the right of Fig. 1, the side of the case being partly removed. Fig. 3 is a vertical section on the line *xx*, Fig. 1, looking toward the left of said figure. Fig. 4 is a plan of the trip-hammer and connected parts for obtaining the impression from the time-wheels. Fig. 5 is a side view of a portion of the driving mechanism with a ratchet-wheel, hereinafter described, removed to show the parts behind 65 said wheel; and Fig. 6 is a section on the line *yy*, Fig. 3, looking toward the right in said figure and illustrating a detail of construction.

Like characters of reference denote corresponding parts in the several figures.

a is the recording-strip of paper or other material which passes over guide-rollers *b c d*, arranged to guide the strip over a table *e* and underneath the time-wheels *f g*, which 75 may be of any ordinary or suitable construction and which are driven through a shaft *h* from a clock *j* in the manner well known in connection with workmen's time-recorders. The recording-strip is fed intermittently at 80 each operation of the machine from a reel *k* to a reel *l* by means of feed-rollers *m*, which are arranged to grip the said strip in any suitable manner. For example, the spindle of the top roller works in a slot 55 in the bearing-plate 56 and is kept pressed down by springs 57. The handle *n* for working the machine is shown projecting through a curved slot *o* in the case of the machine. It is attached to a crank-arm *p*, which is secured on a shaft *q*, 85 mounted in bearings in a suitable frame *r*, which carries the whole of the mechanism. *s t* are two other shafts arranged parallel to the shaft *q*.

u v w are parallel crank-arms on the shafts 95 *q s t*, respectively, and *z* is a link or rod connecting said crank-arms. The crank-arm *u* is fixed on the shaft *q*; but the crank-arms *v w* are loose on their shafts *s t*. By this construction when the shaft *q* is oscillated by 100 moving the handle *n* to and fro the cranks *v w* oscillate in unison therewith. It is only necessary to move the handle *n* in one direction by hand, the return movement being ef-

2
fected by a spring 1, connected at one end to the frame *r* and at the other end to an arm 2, fixed on the shaft *q*. The cranks *u v w* are shown duplicated in the drawings; but this 5 is not necessary, as single cranks may be used. The lower feed-roller *m* is geared to the shaft *s* by toothed wheels 3 4 5. On said shaft *s* are fixed a pair of ratchet-wheels 6 7, having their teeth pointing in opposite directions. These ratchet-wheels are both seen in Fig. 6, while in Fig. 5 the front wheel 6 is removed, together with one of the crank-arms *v*, so as to show the rear wheels 7.

8 9 are spring-controlled pawls pivoted on 15 the crank-arm *v* and engaging, respectively, with the ratchet-wheels 6 7. The wheel 6 serves for feeding the recording-strip forward and the wheel 7 for feeding it backward.

In order that the backward movement of 20 the strip may be less than the forward movement, I provide as follows—that is to say, loosely mounted on the shaft *s* is a cam 10, which is fixed in position by a screw 11, passing through a slot 12 in the cam and screwing 25 into the frame *r*. The pawl 9 is furnished with a projection 13, which rides upon the edge of the said cam, which edge is eccentric to the shaft *s*, so that as the crank-arm *v* moves around to drive the ratchet-wheel 7 the 30 pawl 9 is gradually drawn out of engagement with the teeth of the ratchet-wheel and becomes entirely disengaged before the crank-arm has completed its stroke, whereupon the backward movement of the recording-strip ceases. By adjusting the cam, which the slot 35 12 permits of, the angular movement of the crank-arm *v* before its pawl becomes disengaged from the ratchet-wheel 7 can be regulated, and therefore the extent of backward 40 movement of the recording-strip may be adjusted to suit any requirements.

The shaft *t* is driven in one direction by a spring-controlled pawl 15, pivoted on the crank-arm *w* and engaging with a ratchet-wheel 16, fixed on the shaft *t*. On the said shaft *t* is also fixed a toothed wheel 17, which gears with a pinion 18, connected to a radially-slotted friction-disk 19, that bears lightly against the inner flange of the reel *k* and drives 45 said reel by friction. In a similar way the reel *l* is driven by a friction-disk connected to a pinion 20, gearing with the wheel 3. By this method of driving the feed of the recording-strip in both directions is controlled solely by 50 the rollers *m* and the reels or spools *k l* take up all slack in the strip. The friction between the disk 19 and reel *k* is sufficient to turn said reel so as to take up any slack in the strip, but is not sufficient to drag the 55 strip and rotate the feed-rollers *m* and the connected gears, so that the movement of the strip will cease, as above described, when the pawl 9 becomes disengaged from the ratchet-wheel 7. It is obvious that the reels *k* and *l* may be arranged directly on the shafts *t* and *s*, respectively.

The case of the machine is formed with a

sloping desk 21, in which is an opening 22, immediately above the table *e*. This opening is closed by a plate or shutter 23, except 70 at such times as the recording-strip is in the proper position for receiving the autograph. Said shutter is pivoted at 24, Fig. 1, and is connected by a link 25 to a tappet 26, pivoted at 27. When the handle *n* is drawn forward 75 by the operator, the crank-arm *w* strikes the tappet 26 when near the end of its movement and moves the shutter 23, thus uncovering the recording-strip, and when the handle *n* is returned to its normal position, the shutter 23 80 falls back by gravity, the same being supported on an inclined surface, and closes the opening again, or the shutter 23 may be returned positively by an arm 30, connected to the crank *w*, as indicated in Fig. 3, said arm 85 30 also preventing the shutter from being moved to uncover the recording-strip so long as the handle *n* remains in its normal position.

In order that the records may be made in 90 the correct position on the recording-strip, it is necessary to prevent the return of the handle *n* before a complete stroke is made. For this purpose I fix a ratchet-segment 31 on the shaft *q*, with which ratchet there engages a 95 pawl 32, pivoted to the frame *r*. So long as this pawl is engaged with the ratchet the handle *n* cannot be returned. At the completion, however, of the stroke of the handle *n* a projection 33 on the ratchet 31 raises the 100 pawl 32, whereupon a swinging latch 34, having a shoulder 35, drops underneath the tail end 36 of the pawl and so maintains said pawl out of engagement with the ratchet, and the handle *n* can then be returned. At the 105 completion of the return movement of the handle another projection 37 on the ratchet slides up the inclined edge 38 of the swinging latch and displaces said latch laterally, thereby again releasing the pawl 32 and allowing said pawl to become reengaged with the ratchet 31. I may also provide an exactly similar ratchet and pawls working in the opposite direction to prevent the handle being pulled forward again before the backward movement has been completed. 115

The automatic impression on the recording-strip is obtained by a spring-controlled trip-hammer 40, pivoted at 41 and tripped by a pin 42, acting on the tail end 43 of the hammer. The said pin is fixed in a disk 44, secured on a shaft 45, that is geared by a pinion 46 and toothed segment 47 with the shaft *q*. When the pin 42 escapes past the tail end 43 of the hammer, the latter being thus suddenly 120 released is driven by its spring 48 against the recording-strip *a*, immediately underneath the type-wheels, and an impression is obtained on the said strip by the aid of an ink-ribbon 50. The tail end 43 of the hammer is constructed to swing loosely in one direction, so that the pin 42 can be returned without affecting the hammer. The ink-ribbon 50 passes between the time-wheels *f g* 125 130

and the recording-strip α , being guided by a roller 51. The ribbon-spools 52 53 may be actuated in any known or suitable manner to move the ribbon after each impression is made.

The operation of my improved device is as follows—that is to say, the handle n is drawn toward the operator to its full travel, thus moving the shutter 23 away from the opening 22 and exposing that portion of the recording-strip α beneath said opening. While the handle is held in this position the operator writes his name upon the recording-strip and then releases the handle, which is immediately returned by the spring 1. In the return movement the opening 22 is closed again by the shutter 23 and the recording-strip is fed forward sufficiently to bring the name just written thereon in line with the time-wheels $f g$, at which instant the hammer 40 is released and an impression obtained by the time-wheels opposite said name, thus indicating the time at which the autograph is recorded. When the handle is next operated, the recording-strip α is drawn back again, but not so far as it was moved forward on the previous operation, so that the next portion of strip exposed at the opening 22 is not the same as but is closely adjacent to that last written upon. In this way the successive records are brought as close together as may be desired, thus avoiding waste of paper and at the same time the place where the autograph is made is so far removed from the time-wheels that the writer is not cramped for room.

The autograph-record and the automatic record may be made one above the other or they may be made side by side.

40. What I claim is—

1. In a time and autograph recorder, the combination of a recording-strip, feed-rollers for feeding said strip, an actuating-handle, and intermediate mechanism between the handle and the feed-rollers, whereby when the handle is moved in one direction it feeds the strip backward through a definite distance and when it is moved in the other direction it feeds it forward through a greater distance, for the purpose specified.

2. In a time and autograph recorder, the combination of a recording-strip, feed-rollers for feeding said strip, a table over which said strip passes, time-printing devices, and hand-controlled mechanism for actuating the feed-rollers whereby the strip is first moved backward by one movement of the handle to the proper position for receiving the autograph,

and is then moved forward, by a reverse movement of the handle, to bring the autograph 60 into juxtaposition with the time-printing devices, substantially as described.

3. In a time and autograph recorder, the combination of a recording-strip, feed-rollers, an autograph-table, time-printing devices, a handle for actuating the feed-rollers, and intermediate mechanism between said handle and feed-rollers, said mechanism comprising a pair of pawl-actuated ratchet-wheels arranged to work in opposite directions, one to feed the strip backward and the other to feed the strip forward, and a cam engaging one of said pawls to throw same out of gear before the completion of its stroke, substantially as described. 75

4. In a time and autograph recorder, the combination of a recording-strip, feed-rollers, an autograph-table, time-printing devices, a handle for actuating the feed-rollers, and intermediate mechanism between said handle 80 and feed-rollers, said mechanism comprising a pair of pawl-actuated ratchet-wheels arranged to work in opposite directions, one to feed the strip backward and the other to feed the strip forward, an adjustable cam engaging one of said pawls to throw same out of gear before the completion of its stroke, said cam being adjustable to allow of varying the extent of backward movement of the recording-strip, substantially as described. 85

5. In a time and autograph recorder, the combination of a recording-strip, feed-rollers, hand-actuated mechanism for moving the strip first backward and then forward, and friction-driven reels, for taking up the slack 95 in the said strip, substantially as described.

6. In a time and autograph recorder, the combination of a recording-strip, feed-rollers, an autograph-table, time-printing wheels, hand-actuated mechanism for moving the strip first backward to receive the autograph and then forward to receive the impression from the time-wheels, a handle for working said mechanism, and means to prevent the return of the handle before the completion of 105 its stroke, while allowing it to return when the stroke has been completed, substantially as described.

In testimony whereof I have hereunto set my hand in presence of two subscribing witnesses. 110
